UNITED STATES PATENT OFFICE.

JOSEPH FAFARD, OF THREE RIVERS, QUEBEC, CANADA.

COIN-SORTER FOR FARE-BOXES.

1,128,672.

Specification of Letters Patent. Patented Feb. 16, 1915.

Application filed January 9, 1914. Serial No. 811,146.

To all whom it may concern:

Be it known that I, JOSEPH FAFARD, a subject of the King of Great Britain, residing at No. 3 Celina street, Three Rivers, Province of Quebec, Canada, have invented certain new and useful Improvements in Coin-Sorters for Fare-Boxes; and I do hereby declare that the following is a full, clear, and exact description of the invention, such as will enable others skilled in the art to which it appertains to make and use the same.

The invention to be hereinafter described relates to coin sorters for fare boxes.

15 In order to more clearly disclose the construction, operation, and use of the invention, reference should be had to the accompanying drawings forming part of the present application.

20 Throughout the several figures of the drawings like reference characters designate the same parts.

In the drawings: Figure 1 is a central, vertical, longitudinal, cross section through the invention, applied; Fig. 2 is a like view, through a modified form; Fig. 3 is a like view through a second modification; Fig. 4 is a top plan view of the sorting tube, removed; and Fig. 5 is a side elevation of the 30 same.

The main objects of the invention are to provide a simple, efficient, economical, durable, and compact coin sorter which may be readily and easily applied to the present well known fare boxes with practically no important change; and one which will quickly, accurately, and positively sort the coins properly as they are inserted through the usual fare slot.

40 Referring to the drawings in detail, and especially to Figs. 3, 4, and 5, 1 indicates a top plate adapted to be bolted or otherwise removably secured to the under side of the top of the usual fare box and provided with 45 a central circular opening from which depends a tube 2, the central opening being adapted to fall directly beneath the fare slot when the top plate is in place. The central opening in plate 1 is large enough to allow 50 passage of any coin up to and including a 25 cent piece. Within the tube are arranged two or more oppositely inclined plates 3, one below the other, and each having a coin passage smaller in diameter than the one 55 next above. Each plate is extended through

a slot 4 in the side wall of the tube and forms a coin chute. Also, each of these extended portions projects into a separate compartment of the fare box formed by partitions 5, and the bottom of the tube 60 leads into the central compartment. Thus, if a 25 cent piece is dropped into the tube, it will fall on to the top plate and be delivered out through the first slot of the tube and into the compartment at the right of Fig. 3; a 10 cent piece will pass through the opening in the first plate, fall on to the second plate, and be delivered through the second slot and into the compartment at the left of Fig. 3; and a 5 cent piece will pass 65 through the openings in both plates and fall into the middle compartment. In addition, a fourth compartment may be provided for the tickets, with the usual ticket slot above the same. The usual spring suspended trap door 6 with spring push rod 7 is provided, the only difference being that the trap door is slotted on account of the partitions, as clearly shown in Fig. 3. Each compartment is provided with a pivot door 8, of course, 70 to permit the removal of fares.

The construction shown in Fig. 2 is the same as in Fig. 3, except that the plate 1 is made either integral with or solidly secured to the inside of the top of the fare box, instead of being separate.

In Fig. 1 only two sizes of coins are provided for, the third compartment being used for tickets. Otherwise, the construction of Fig. 1 is the same as Fig. 2.

It is thought that the construction, operation, and use of the invention will be clear from the preceding detailed description.

Changes may be made in the construction, arrangement, and disposition of the several 95 parts of the invention without in any way departing from the field and scope of the same, and it is meant to include all such within this application wherein only a preferred form has been disclosed.

Having thus fully described my invention, what I claim as new and desire to secure by Letters Patent is:

1. In combination with a fare box, a coin sorting tube provided with a coin delivery 105 slot in one side, and an inclined plate in said tube leading to said slot and provided with a coin passage of less diameter than said tube.

2. In combination with a fare box, a coin 110

sorting tube provided with coin delivering slots in its sides, and a plurality of oppositely inclined plates in said tube leading to said slots and provided with coin passages 5 of successively decreasing diameter.

3. In combination with a fare box, a plate, means for connecting said plate to said box, a coin sorting tube carried by said plate and provided with a coin delivering slot in one side, and an inclined plate in said tube leading to said slot and provided with a coin 10 passage of less diameter than said tube.

4. In combination, a fare box provided with a plurality of compartments, a coin delivery tube mounted therein and having coin delivery slots in its opposite sides, and a plurality of superposed inclined plates 15 mounted in said tube and leading to said

slots and communicating with the compartments of the box, respectively.

5. In combination; a fare box provided with a plurality of compartments; a vertical tube mounted in the upper end thereof and provided with slots in its sides; and superposed inclined plates leading to the said 25 slots, and communicating with the compartments of the said box, respectively, the said plates being provided with downwardly decreasing openings.

In witness whereof I have hereunto set 30 my hand in the presence of two witnesses.

JOSEPH FAFARD.
